DESIGN FOR A BOTTLE DISPLAY CARTON

Robert B. Karoff, New York, N. Y.

Application May 29, 1944, Serial No. 113,789

Term of patent 3½ years

(Cl. D80—5)

To all whom it may concern:

Be it known that I, Robert B. Karoff, a citizen of the United States and a resident of the city of New York, in the county of New York and State of New York, have invented a new, original, and ornamental Design for a Bottle Display Carton, of which the following is a specification, reference being had to the accompanying drawing, constituting a part thereof, in which

Fig. 1 is a top plan view of a bottle display carton showing my new design;

Fig. 2 is a side elevational view;
Fig. 3 is an end elevational view; and
Fig. 4 is a perspective view with the bottles removed and the top of the container in open position.

I claim:
The ornamental design for a bottle display carton, as shown.

ROBERT B. KAROFF.
